ATTORNEYS

UNITED STATES PATENT OFFICE.

WILLIAM B. DURGIN, OF CONCORD, NEW HAMPSHIRE.

DESIGN FOR A HANDLE FOR SPOONS, &c.

SPECIFICATION forming part of Design No. 20,591, dated March 24, 1891.

Application filed February 18, 1891. Serial No. 381,972. Term of patent 7 years.

To all whom it may concern:

Be it known that I, WILLIAM B. DURGIN, a citizen of the United States, residing at Concord, in the county of Merrimac and State 5 of New Hampshire, have invented and produced a Design for the Handles of Spoons and other Flat Ware, of which the following is a specification, reference being had to the accompanying drawings, in which the figure 10 represents a face view of a spoon having my design produced on the handle thereof.

The design consists of the figure *a*, representing a woman in erect posture, and the figure *b*, representing the door of a building, the 15 figure of the woman appearing as if standing

in front of said door. Below or inward from said figures appear the figures *c d*, representing, respectively, boughs or branches and a ribbon twined therearound, the two figures *c d* merging into the bowl of the spoon. 20

The leading feature of my design consists in the figures *a b*.

I claim—

The design for the handles of spoons and similar flat ware, as herein shown and de- 25scribed.

WILLIAM B. DURGIN.
